(57) **CLAIM**

The ornamental design for an activator shield, as shown and described.

DESCRIPTION

FIG. 1 is a top plan view of an activator shield showing my new design;

FIG. 2 is a front view thereof;

FIG. 3 is a rear view thereof;

FIG. 4 is a side view thereof;

FIG. 5 is another side view thereof, opposite that of FIG. 4;

FIG. 6 is a bottom plan view thereof; and,

FIG. 7 is a cross-sectional view thereof taken along line 7-7 of FIG. 1.
